Patented Jan. 9, 1917.

UNITED STATES PATENT OFFICE.

CHURCHILL G. GRAVES, OF ROANOKE, VIRGINIA, ASSIGNOR TO THE SEWARD TRUNK AND BAG COMPANY, OF PETERSBURG, VIRGINIA, A CORPORATION OF VIRGINIA

REISSUED

WARDROBE-TRUNK.

1,212,139.

Specification of Letters Patent.

Patented Jan. 9, 1917.

Application filed May 23, 1916. Serial No. 99,312.

To all whom it may concern:

Be it known that I, CHURCHILL G. GRAVES, a citizen of the United States, residing at Roanoke, in the county of Roanoke and 5 State of Virginia, have invented certain new and useful Improvements in Wardrobe-Trunks, of which the following is a specification.

This invention relates to wardrobe trunks 10 and among the objects thereof is to provide a compact trunk which may be readily taken apart, but which is of sturdy construction when closed; to provide in connection with such a trunk a hanger-rack suitable for the 15 support of garment hangers, it being one of the objects to provide a hanger-rack that may be removed from the trunk as a unit when the latter is opened.

Another object is to provide a hanger-rack 20 with extendible portions, which extensions also serve as a garment press.

With these and other objects in view the invention consists in the formation, combination and arrangement of elements as will be 25 herein described and particularly claimed.

In the accompanying drawings, Figure 1 is a front elevational view of a portion of a trunk having my invention applied thereto. Fig. 2 is a plan view of the same. Fig. 3 30 is a broken vertical section taken approximately on the line 3—3 of Fig. 1. Fig. 4 is a side elevational view of one hinge member and Fig. 5 a similar view of the coöperating hinge member as used in connection 35 with the present invention.

Referring now to these drawings wherein like parts are similarly designated wherever they occur, 1 represents the front portion of the trunk of my invention, and 40 2 the rear portion thereto.

3 represents the lid which is hinged to the top of the rear wall of portion 2.

The portions 1 and 2 are hinged together along the adjacent vertical edges by means 45 of the hinges 4. When the portion 1 is closed upon the portion 2 the lid 3 may be swung around and when closed it overlaps the portions 1 and 2 at 5 thereby clamping and interlocking the same together.

50 The hinges 4 by means of which the portions 1 and 2 are hinged together are constructed as follows: Secured to the portion 2 is a male hinge member 4^a, and secured to the portion 1 is a female hinge member 4^b. The hinge member 4^a is provided with

a pintle 4^c, there being a shoulder 4^d at the bottom thereof. The portion 4^b is provided with a co-engaging eye portion 4^e, the said eye of which accommodates the pintle 4^c and the bottom 4^f of the same bearing upon the 60 shoulder 4^d. A plurality of these shoulered pintle members are secured to the portion 2 of the trunk and a corresponding number of the eye members are disposed at intervals along the edges of the portion 1 65 so as to aline with the pintles on the other portion. The pintles are all turned in one direction so that when the lid of the trunk is swung back and the trunk opened the portion 1 may be lifted off the hinges and 70 placed in another part of the room. Thus each portion of my trunk will serve as an individual article of furniture in a room.

My trunk is provided further with a rack for clothes hangers, the same consisting of 75 a frame work of dimensions suitable for admission within the upper portion of the trunk; this frame work is composed of parallel members 6 which are disposed along either side of the cavity of the trunk near 80 the top of same with a connecting member 7 extending from one to the other across the rear wall of the trunk and near the top thereof. From these parallel members there are extending downwardly and rearwardly 85 to the rear wall of the trunk a pair of braces 8 and connecting the lower ends of these braces is a second connecting member 9 which extends likewise across the rear wall of the trunk and at some distance below the 90 member 8. A vertical tie 10 connects the members 7 and 9, this bar extending slightly above the member 7, and being provided with an eye 11 which serves as means for hanging up the hanger-rack when removed 95 from the trunk upon any co-engaging means, as for example a nail in the wall.

Affixed to the inner walls of the trunk are brackets 12, the same being provided with outstanding corrugations 13 which overlie 100 offset portions of the parallel members 6 and serve to retain these parallel members 6 in their guides or ways. Thus are formed co-engaging and interlocking slideways in and out of the trunk for the parallel members 105 6 in their brackets 12. These brackets are provided with overturned portions 14 at the bottom with a space between which accommodates the lower edges 15 of the parallel members 6. The parallel members are pro- 110

vided with inwardly over-turned portions 16 at their upper edges with an interval between the two walls of the metal. The turned ends of the connecting bar 7 and the upper ends of the braces 8 are disposed within this space the rivets 17 and 18 passing through the two walls of the parallel members and tying the parts together respectively. The bottoms of the braces 8 are turned inwardly and to the rear of the same at 19 are riveted the ends of the cross member 9. Thus it will be seen that the entire hanger-rack may be slid out of the trunk as a unit when the front is removed and 15 may be carried about and hung in another part of the room. In order to provide simple means for removing the hanger-rack and for carrying the same when removed from the trunk I have provided a bail 20, 20 the side members 21 of which are pivoted at 22 to the parallel members 6, the cross bar 23 extending from one side member 21 to the other; this bail as shown may be swung down to the position as indicated in dotted 25 lines in Fig. 3 or may be raised for carrying to the full line position. The bail preferably extends above the limits of the cavity of the trunk when the same is in the upright position. The hangers slide upon 30 rounded upper edge of the parallel members and may be slid back close together when the trunk is closed. The bail members 21 are pivoted to the members 6 above the convolutions 13 and are then bent outwardly at 24 so as to give clearance for 35 the ends of the garment hangers.

In order that the hangers 25 may be separated and the garments readily removed I provide extensions 26 from the slideways or 40 parallel members 6, the same being pivoted at 27 to the parallel members and the inner ends of the same being provided with elongated slots 28. Pins 29 are inserted through the walls of the parallel members 6 and the 45 slots 28 slidably accommodate the pins 29 which pass therethrough. The inner ends of the extension 26 extend between the walls of the parallel members 6 and underlie over-turned portions 16 thereof, so that when the 50 pins 29 are in the outer ends of the slots 28 the inner ends of the extensions will fall well under the overturned portions 16 and the extensions will be thereby supported against falling. When the extensions are 55 drawn outward so that the pins occupy the rear ends of the slots the extensions may be swung downward about the pins as an axis.

At the outer ends of the extensions 26 I provide a roller 30 which extends from one 60 to the other of the same, the roller being journaled at 33 in the ends of the extensions. This roller is preferably covered with velvet or similar material and constitutes a roller clothes press. When the hangers 25 65 with the garments thereon are pushed back

to the rear of the trunk, the extensions which comprise the roller clothes press may be swung downwardly and rearwardly, pressing the garments tightly against the rear wall of the trunk. Notched brackets 70 31 are provided on the inner walls of the trunk which coöperate with projecting pins 32 from the roller to hold the roller press against return movement. The notches in the brackets 31 are open at their upper edges 75 75 for the admission of the pins 32, and the roller is lifted as a unit to bring the pins 32 into and out of engagement with the notches; hence in order to apply and release the roller from these notches the lower ends of 80 the extensions are slotted at 34 for the journals 33 instead of being simply pierced. When the roller is inserted in a suitable pair of notches it may then be rotated and the clothing thereby drawn down by the movement thereof instead of remaining bunched and wrinkled.

The brackets 31 shown in the present embodiment are of a well-known commercial form made by punching a series of substantially rectangular holes in a flat plate of thin metal, and then, bending this plate of metal into right-angled portions along a line passing through the series of holes, and then again bending these portions of the 95 plate along parallel lines so as to provide edges suitable for contacting the sides of the trunk. Retaining rivets are passed through one of these edges and the trunk walls. Thus when these plates are so formed into 100 brackets the rectangular holes form the required notches, the upper portions of the holes providing horizontal openings for the admission of the ends of the pins 32 and the lower portions of the holes forming the retaining notches which prevent the return movement of the roller press until the roller is lifted upward in the slots 34 so as to raise the projecting ends of the pins 33 entirely clear of the notches in the brackets 31. 110 While this form of notched bracket is depicted in the drawings, it will be understood that the particular form is immaterial, this style being used because it may be purchased from manufacturers of trunk hardware. 115

I have thus described the present embodiment of my invention. It will be evident that those skilled in the art may make alterations in the same within the scope of the claims without departing from the spirit 120 thereof.

What I claim is:

1. In a wardrobe trunk, a hanger rack comprising a frame-work of dimensions suitable for admission within the said trunk, 125 said frame-work embodying spaced parallel members disposed along both sides of the cavity of the trunk near the top thereof and having a connecting member extending from one of said parallel members to the 130

- other along the rear of the trunk, braces extending from the said parallel members downwardly and rearwardly to the rear wall of said trunk and having a connecting member extending from one brace to the other against the rear wall of the trunk, a vertical tie member connecting the last said connecting member with the first one, brackets affixed to the inside of the side walls having slideways adapted to receive and slidably accommodate the said parallel members, the said frame-work being slidably removable from the said trunk and said brackets as a unit.
2. In a wardrobe trunk, a hanger-rack comprising a frame-work of dimensions suitable for admission within the said trunk, said frame-work embodying spaced parallel members disposed along both sides of the cavity of the trunk near the top thereof and having a connecting member extending from one of said parallel members to the other along the rear of the trunk, braces extending from the said parallel members downwardly and rearwardly to the rear wall of said trunk and having a connecting member extending from one brace to the other against the rear wall of the trunk, a vertical tie member connecting the last said connecting member with the first one, brackets affixed to the inside of the side walls having slideways adapted to receive and slidably accommodate the said parallel members, the said frame-work being slidably removable from said trunk and said brackets as a unit, means in the rear of said frame-work and near the top thereof formed for engagement with a supporting member.
3. In a wardrobe trunk, a hanger-rack comprising a frame-work of dimensions suitable for admission within the said trunk, said frame-work embodying hanger ways along the inner walls of the trunk, brackets secured to the inner walls of the trunk adapted to retain and support the said hanger-rack, a lid on said trunk adapted to retain the said hanger-rack within the said brackets, and said hanger-rack being removable as a unit from the said brackets and trunk when the said lid is open, and having means for its support against a wall when removed from the said trunk.
4. In a wardrobe trunk, a hanger-rack comprising a frame-work of dimensions suitable for admission within the said trunk, said frame-work embodying hanger ways along the inner walls of the trunk, brackets secured to the inner walls of the trunk adapted to retain and support the said hanger-rack, a lid on said trunk adapted to retain the said hanger-rack within the said brackets, the said hanger-rack being removable as a unit from the said brackets and trunk when the said lid is open, and a bail extending from side to side of the said frame-work and being pivoted thereto, the said bail being adapted to be swunk about its pivot as an axis from an upright position above the cavity of the trunk to a substantially horizontal position in which latter position the bail falls within the cavity of the trunk.
5. A wardrobe trunk having an open front side, a pair of hanger ways disposed along the inside of the side walls of the trunk and near the top thereof, said hanger ways having projecting pins near their front ends and having overturned portions above the said pins, outward extensions from said hanger ways having elongated slots at their inner ends, the said slots embracing and accommodating the said pins and the inner ends of the said extensions underlying the said overturned portions of the hanger ways, the slots in the said extensions being so disposed that the inner ends of the extensions will engage the overturned portions of the hanger ways when the pins are in the outer ends of the slots and thereby support the extensions in extended position and being formed further so that when the said pins occupy the rear ends of the said slots the said extensions may swing downwardly and rearwardly about said pins as an axis, a transverse member extending transversely of the trunk from the outer end of one of said extensions to the outer end of the other, and means carried by the inner faces of the side walls of the trunk for holding said extensions from return movement.
6. A wardrobe trunk having an open front side, a pair of hanger ways disposed along the inside of the side walls of the trunk and near the top thereof, said hanger ways having projecting pins near their front ends and having overturned portions above the said pins, outward extensions from said hanger ways having elongated slots at their inner ends, the said slots embracing and accommodating the said pins and the inner ends of the said extensions underlying the said overturned portions of the hanger ways, the slots in the said extensions being so disposed that the inner ends of the extensions will engage the overturned portions of the hanger ways when the pins are in the outer ends of the slots and thereby support the extensions in extended position and being formed further so that when the said pins occupy the rear ends of the said slots the said extensions may swing downwardly and rearwardly about said pins as an axis, a transverse roller extending from one of said extensions to the other, the said roller being journaled in the outer ends of the said extensions, and means carried by the inner faces of the side walls of the trunk for holding

said roller and extensions from return movement.

7. A wardrobe trunk having an open front side, a pair of hanger ways disposed along the inside of the side walls of the trunk and near the top thereof, said hanger ways having projecting pins near their front ends and having overturned portions above the said pins, outward extensions from said hanger ways having elongated slots at their inner ends, the said slots embracing and accommodating the said pins and the inner ends of the said extensions underlying the said overturned portions of the hanger ways, the slots in the said extensions being so disposed that the inner ends of the extensions will engage the overturned portions of the hanger ways when the pins are in the outer ends of the slots and thereby support the extensions in extended position and being formed further so that when the said pins occupy the rear ends of the said slots the said extensions may swing downwardly and rearwardly about said pins as an axis, a transverse roller extending from one of said exten-

sions to the other, the said roller being journaled in the outer ends of the said extensions, and means for holding said roller end extensions from return movement, said means embodying arcuate notched plates secured to the inner faces of the trunk walls and the said roller being provided with projecting pins adapted to engage the notches in the said notched plate. 35

8. In a wardrobe trunk, clothing hangers, means for supporting the same adjacent a wall of the trunk, a press adapted to be forced against the clothing hung therefrom and to hold the same against the adjacent trunk wall, said press comprising movable brackets with a roller journaled therein, said roller being disposed to contact the clothing and being revoluble thereagainst. 40

In testimony whereof I affix my signature in presence of two witnesses.

CHURCHILL G. GRAVES.
